UNITED STATES PATENT OFFICE.

FRANS BERTIL WENDEL, OF BROOKLYN, NEW YORK.

CONTAINER.

Application filed October 4, 1921. Serial No. 505,227.

To all whom it may concern:

Be it known that I, FRANS BERTIL WENDEL, a citizen of the United States, and a resident of the city of New York, borough 5 of Brooklyn, in the county of Kings and State of New York, have invented a new and Improved Container, of which the following is a full, clear, and exact description.

10 This invention relates to containers for powdered or granulated materials such as spices, condiments, or the like, and refers more particularly to an improved means for discharging or removing the contents 15 thereof.

The invention contemplates a container of the character described provided with a closure which affords means for sifting the contents or discharging the same in quantities, which closure is rotatably mounted on the top of the container for selectively shifting the same to its various discharge positions.

As a further object the invention contemplates interengageable friction means on the closure and container top which are adapted to coact to retain the closure in its various shifted positions.

A still further object of the invention resides in the provision of a discharge means and a destructible seal coacting therewith which initially operates to seal the discharge means in closed position.

As a further object the invention aims to provide a discharge closure for a container of the character described which eliminates sharp points or edges which might tend to injure the hands of the user in opening the same and which is applicable to containers 40 of various shapes and sizes.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general 45 meaning of the terms in which the claims are expressed and by variations in the phraseology of the same.

In the drawings—

Figure 1 is a side elevation of the container constructed in accordance with the

invention and illustrating the discharge means sealed in closed position.

Figure 2 is a plan view thereof.

Figure 3 is a similar view illustrating the closure head shifted to a position for discharging the contents.

Figure 4 is an enlarged fragmentary sectional view taken approximately on the line 4—4 of Figure 2.

Figure 5 is a similar view taken approximately on the line 5—5 of Figure 3.

Figure 6 is a similar view taken approximately on the line 6—6 of Figure 2.

Referring to the drawings by characters of reference, 10 designates the body of a 70 container of oblong configuration in cross section. The upper end of the body is closed by a permanently attached top 11 which is provided with a centrally disposed convex boss 12 and diametrically disposed upstanding bosses 13 and 14 on opposite sides thereof, said bosses 13 and 14 being of oblong configuration in plan view. Use is made of a closure head 15 which is of substantially the same size and configuration as the upper 80 end of the container body and which is provided with a centrally disposed upstanding concave boss 16 adapted to snugly receive and fit over the boss 12 of the top 11. The bosses 12 and 16 are provided with concentrically aligned apertures through which a rivet 17 is passed to afford means for rotatably associating the closure head with the top of the container. The closure head is provided with complementary upstanding 85 bosses 18 and 19 providing on their under faces recesses adapted to snugly receive the bosses 13 when said bosses are brought into alignment. The peripheral edges of the closure head 15 are provided with an upstanding continuous flange 20 disposed in vertical alignment with the sides of the body and with the upper edges thereof in a horizontal plane slightly above the central boss and rivet. The central boss 12 of the top 100 105 is provided at diametrically opposite points with discharge ports 21 and 22 and with sifter openings 23 arranged at right angles thereto to provide a substantially annular series of discharge ports through the central boss 12 of the top 11. The closure head 15 is provided with a single discharge opening 24 in the central boss 16 thereof which is adapted to be selectively brought into registration with either of the discharge 110

ports 21 or 22 or the sifter openings 23 when the closure head is rotated relative to the container. Normally when the closure head is in the position illustrated in Fig. 2 with the boss 13 frictionally engaged in the boss 18 and the boss 14 frictionally engaged in the boss 19, the single discharge opening 24 of the closure head is disposed out of alignment with all of the discharge ports to close the container against the discharge of its contents. When in this position the can is offered for sale, a seal consisting of a paper strip 25 is arranged to lie over the upper side walls of the body and the outer sides of the flange as illustrated in Fig. 1 in order to insure to the purchaser the genuine and unadulterated article, said seal being designed to be broken automatically by turning or twisting the closure head relative to the body. The distance between the inner edges of the bosses 13 and 14 is substantially equal to the distance between the outer sides of the flanges of the closure head whereby upon turning the same a quarter turn or at right angles said inner edges of the bosses 13 and 14 will coat with the side walls of the flanges to frictionally retain the closure head in a position to bring the discharge opening 24 in alignment with either of the discharge ports 21 or 22. This will permit the pouring or discharging of a quantity of the contents from the container body. When it is desired to use the sifter openings 23 for sifting the contents therefrom, the closure head is rotated a half turn to bring the discharge port 24 in registry with the sifter openings 23 in which instance the bosses 14 and 18 and 13 and 19 will interengage to frictionally retain the closure head in this position. The upstanding peripheral flange 20 of the closure head affords ample means for manipulating the same to effect its turning or shifting to the various positions, and the inherent resiliency of the material from which the body top and closure head are constructed will insure the snapping of the bosses 13, 14, 18 and 19 into frictional interengagement with each other to prevent casual displacement of the same.

While the device has been illustrated and described as being specially adaptable to containers of oblong configuration in cross section, it is to be understood that the same may be employed equally as well in connection with square, round or other shapes of containers.

I claim:

1. A container comprising a body having a closed top end of oblong configuration and provided with an annularly arranged series of discharge openings, a closure conforming in shape to the closed top end of the container and rotatably mounted thereon, said closure having a discharge opening adapted to be disposed in registry with any one of said series of discharge openings in the top of the body or disposed out of registry therewith for closing the same, complementary bosses and depressions provided respectively on the closed top end of the body and in the under side of the closure adapted for interengagement to retain the major axis of the closed top end of the body and the closure in alignment, the said bosses engageable with the side edges of the closure for holding the major axis of the same at right angles to the body. 60
2. In a container of the character described, an oblong body having a closed top end provided with an annularly arranged series of discharge openings, bosses upstanding from said top end, an oblong closure rotatably mounted on the closed end of the container and of such width that the side edges will be engaged by the bosses when the closure is opened, said closure having a discharge opening therein, and depressions in the underside of said closure adapted for interengagement with the bosses for retaining the same in closed position. 65
3. A container of the character set forth comprising a body having a top provided with an annularly arranged series of discharge openings, a closure conforming in shape to the body rotatably mounted on said top and provided with a discharge opening adapted to be respectively disposed in registry with any one of said series of discharge openings in the top of the body or disposed out of registry therewith for closing the same, interengageable means on the top and the closure adapted to coat for frictionally maintaining the discharge openings in or out of registry, and a destructible seal coating respectively with the periphery of the closure and of the container body for initially sealing the same to close the discharge opening adapted to be broken open by relative rotation of the closure head with respect to the body. 70 75 80 85 90 95 100 105 110

FRANS BERTIL WENDEL.
